(57) **CLAIM**

The ornamental design for a vessel having a twin deep V technology hull, as shown and described.

DESCRIPTION

FIG. 1 is a right-side (i.e. starboard-side) perspective view of a vessel having a twin deep V technology hull.

FIG. 2 is a left-side (i.e. port-side) perspective view.

FIG. 3 is a right-side elevational view.

FIG. 4 is a left-side elevational view.

FIG. 5 is a front (i.e. bow) elevational view.

FIG. 6 is a back (i.e. stern) elevational view.

FIG. 7 is a top plan view; and,

FIG. 8 is a bottom plan view.

Broken lines in the drawings show environmental structures and are not claimed.

1 Claim, 5 Drawing Sheets
